(57) **CLAIM**

We claim the ornamental design for sports eyewear, as shown and described.

DESCRIPTION

FIG. 1 is a front, side perspective view of sports eyewear; FIG. 2 is a front view of the sports eyewear of FIG. 1; FIG. 3 is a side view of the sports eyewear of FIG. 1; FIG. 4 is a top view of the sports eyewear of FIG. 1; and, FIG. 5 is a bottom view of the sports eyewear of FIG. 1. The ornamental design that is claimed is shown in solid lines in the drawings. The broken (dashed) lines shown in the figures are included for the purpose of illustrating environmental elements only and form no part of the claimed design.
